UNITED STATES PATENT OFFICE.

HOMER M. SINCLAIR, OF HOLYOKE, MASSACHUSETTS, ASSIGNOR TO AMERICAN
TISSUE MILLS, OF HOLYOKE, MASSACHUSETTS, A CORPORATION OF MASSACHU-SETTS.

DESIGN FOR AN ENVELOPE OR SIMILAR CONTAINER.

Application filed February 9, 1929. Serial No. 29,991. Term of patent 3½ years.

To all whom it may concern:

Be it known that I, HOMER M. SINCLAIR, a citizen of the United States, residing at Holyoke, in the county of Hampden and State of Massachusetts, have invented a new, original, and ornamental Design for an Envelope or Similar Container, of which the following is a specification, reference being had to the accompanying drawing, forming part thereof.

The figure is a perspective view of an envelope or similar container showing my new design.

I claim:

The ornamental design for an envelope or similar container as shown.

HOMER M. SINCLAIR.
